PORTABLE REPAIR VULCANIZER

Harold H. Hanson, Waupun, Wis., assignor to
 The Shaler Company, Waupun, Wis., a corpora-
 tion of Delaware

Application October 14, 1932, Serial No. 637,704

7 Claims. (Cl. 18—18)

My invention relates to improvements in portable repair vulcanizers, with particular reference to that type in which a predetermined quantity of fuel in the form of a plate or disk is applied to a metal platen or pan which is clamped upon a patch to be vulcanized to a tire tube or other article.

One object of my invention is to provide a clamping mechanism with means for holding the fuel in contact with the platen during initial combustion and while the platen is being simultaneously held in pressure relation to the rubber to be vulcanized.

Further objects are to provide improved means for centering the platen upon the patch and preventing it from shifting during adjustment of the clamping screw; to provide means for preventing substitution of fuel containing platens having fuel of different quality, fuel with a different rate of combustion, or fuel which cannot be relied upon to deliver a predetermined number of B. t. u.'s to the patch; also to provide means for holding the central portion or portions of the fuel to the platen during combustion to prevent warping, and hold the fuel disk from being lifted by gases accumulating between it and the surface of the platen to which the fuel is applied.

In the drawing:

Figure 1 is a side view of a repair vulcanizer embodying my invention and showing a fuel supporting platen clamped upon a patch applied to a tire tube, the tire tube platen and the portion of the clamping spider being illustrated in section.

Figure 2 is a perspective view of the clamping spider and an associated fuel containing platen in separated relation to each other, a portion of the clamping screw shank being also illustrated.

Figure 3 is an elevation taken at right angles to Figure 1 and showing a modification adapted for vulcanizing elongated patches, the tube, platen, and a portion of the spider being illustrated in section.

Figure 4 is a plan view of the work supporting clamping plate with a fuel containing platen held in position thereon by the clamping spider illustrated in Figure 3, the clamp screw shank being illustrated in cross section.

Like parts are identified by the same reference characters, throughout the several views.

50 The clamping mechanism illustrated in the drawing is of the "C-clamp" type in which a yoke shaped member has a lower arm 10 provided with a fixed work supporting plate 11. An upper arm 12 has an apertured extremity into which a clamping screw 13 is threaded. The clamping

screw has an operating thumb piece 14 at its upper end, and its lower end is provided with a shank 15 having swivel connection at 16 with a clamping spider 17. In the construction shown, a pan-like platen 18 is provided with a fuel disk 19, and the platen is clamped down upon the patch 20 to hold the latter in proper relation to the tire tube 21 during a vulcanizing operation.

In general construction the parts thus far described may be assumed to be of any ordinary type, and a more detailed description is, therefore, deemed unnecessary.

The novel features embodying my invention will now be described.

I provide the platen 18 with marginal notches 24. Preferably these notches are V-shaped and are adapted to receive corresponding V-shaped projections 25 on some of the arms of the spider 17.

These projections 25 may be located on diametrically opposite spider arms, the notches 24 being correspondingly located in the platen 18.

The notches 24 are of sufficient depth to receive the V-shaped projections 25, and while the other arms of the spider may also have V-shaped extremities 26, the edges of these projections are in a different horizontal plane and, in the construction shown, are adapted to engage the upwardly extending margins of a pan-like platen after the projections 25 have entered the notches 24. The parts are so proportioned that simultaneous pressure will be applied to both the notched and unnotched margins of the platen.

If an attempt is made by a dealer or other person to fraudulently substitute platens containing inferior fuel, the improved vulcanizing apparatus cannot be used in connection with such platens unless the latter are similarly notched. Attempts to substitute platens containing inferior fuel are thereby discouraged.

To prevent the fuel from lifting from the platens to which the fuel is applied, I preferably employ V-shaped projections 25 which extend inwardly from the platen marginal notches to bear upon the fuel simultaneously with the engagement of these projections in the bottom of the notches 24. I also provide the arms of the spider with downwardly extending prongs or fuel engaging projections 30, which bear upon the central portion or portions of the fuel to prevent the fuel from lifting during combustion thereof or while the fire is spreading through the fuel mass.

These fuel clamping prongs 30 are more important when the platens are large, or when they are elongated as shown in Figures 3 and 4.

These composition fuels are ordinarily quite porous, and ignition will usually take place at one point where a burning match is applied to the fuel. Therefore, the initially ignited portion 5 of the fuel may generate intense heat before combustion reaches the other portions, and this unequal heating of the fuel mass tends to cause the fuel plate or disk to warp or lift.

Also, gases tend to accumulate underneath 10 the fuel and as the fuel lifts, air is permitted to enter between it and the bottom of the pan and keep the latter comparatively cool, while combustion will then be so accelerated that the fuel bursts into flame and is quickly consumed while 15 out of contact with the platen.

Thus, if the fuel is permitted to lift from the bottom of the pan there is not only a great reduction in heat transfer to the patch, but it is impossible to regulate either the time for completing 20 combustion or the time during which the bottom of the pan will have a vulcanizing temperature, if it ever reaches that temperature. Pronounced warping or lifting of the fuel may thus wholly prevent vulcanization of the patch, although 25 the degree of heat and the time during which the patch will have a vulcanizing temperature may otherwise be very accurately predetermined at the factory where the fuel is made.

It has been found by experiment that the initial 30 lifting of the fuel from the metal is ordinarily accomplished under very light pressure, and that pronounced warping or violent lifting usually occurs after the entry of air to the space between the lifted fuel and the metal. Therefore, by 35 applying a clamping pressure at various points on the fuel disks to prevent such initial lifting of the fuel, air may be kept from entering between the pan and fuel until the heat of the fuel has become largely equalized in all portions 40 thereof and by the time the fuel has become consumed sufficiently to release it from the clamping pressure, the generation of gases will have become less rapid and the porosity of the fuel mass increased to such an extent that there 45 will be no effective lifting or warping pressure.

Also, surface combustion will have been completed and the mass of fuel will be covered by an envelope of ash, underneath which combustion of a self-oxygenating fuel may proceed more slowly 50 with comparatively little generation of gas and continued conduction of a vulcanizing temperature through the metal to the rubber until the desired number of B. t. u.'s have been transmitted.

From the foregoing description, it will be apparent 55 that the user of my improved vulcanizer may rely upon obtaining fuel of uniform quality and upon obtaining uniform results in the use of such fuel, inasmuch as the vulcanizing clamp ensures equality in the conditions under which 60 vulcanization takes place. Factory predetermination of the number of B. t. u.'s to be transmitted to the rubber is thereby made possible 65 within a range of accuracy which assures proper vulcanization of the patch.

In Figures 3 and 4, the structure is substantially 70 the same as in Figures 1 and 2, with the exception that two diametrically opposite spider arms 17a are made relatively long as compared with the other spider arms 17b, thereby adapting the spider for engagement with oval shaped or elongated platens. Also, in Figures 1 and 2, only 75 four spider arms need be used in connection with ordinary small sized platens whereas, for larger

platens, a greater number of spider arms should be provided.

It will, of course, be understood that it is immaterial whether the platens be circular, oval or rectangular in form. The form of the platen will be varied to suit the requirements of the type of operation for which the vulcanizing apparatus is designed. Pan-shaped platens are preferred for the reason that the upwardly extending walls assist in preventing air from entering between the fuel and the metal, and also aid in maintaining heat at margins equal to that at the central portion of the patch. 80 85

I claim:

1. Vulcanizing apparatus including a cup-shaped platen having a notch in one wall, in combination with a clamping member having arms provided with platen engaging portions at different levels adapted to engage the notched and unnotched portions of the platen with substantially equal pressure when the clamping member is in a position of general parallelism with the platen. 90 95

2. Vulcanizing apparatus including the combination of a fuel supporting platen having portions at different levels in a position to receive clamping pressure, and clamping means adapted to engage said portions with substantially balanced pressure when the clamping means is in a general position of parallelism with the platen. 100 105

3. Vulcanizing apparatus including the combination of a cup-shaped fuel containing platen having an upstanding notched wall, a fuel disk on said platen, and a clamping spider associated with centrally connected pressure applying 110 means and having arms, one of which is adapted to engage with the upper margin of said wall and another of which is adapted to engage in the notched portion of said wall and to extend inwardly therefrom at the same level in pressure 115 engagement with the surface of the fuel carried by the platen.

4. Vulcanizing apparatus consisting in the combination of an oblong cup-shaped fuel containing platen having a notch in the wall thereof, in combination with a clamping member having arms of unequal length and different degrees of downward extension, the arm having the greatest downward extension being adapted to engage in said notch at a lower level than other 120 125 of the platen engaging arms operating at a higher level, and means for applying clamping pressure to said member, including a screw in swiveled connection with its central portion, said member being self adjusting for balanced pressure at all points of engagement with the platen. 130

5. In a vulcanizer, the combination of a sheet of prepared fuel and a fuel supporting platen having clamp receiving portions substantially at the level of the upper surface of the fuel and other portions above that level, and a platen 135 engaging clamping member provided with depending projections adapted to simultaneously engage the platen and the platen supported fuel, said clamping member being provided with intermediate depending projections adapted to engage the central portion of the fuel when the first mentioned portions are in engagement with the platen. 140

6. In a vulcanizer, the combination of a platen 145 having raised marginal portions at different elevations and provided with a fuel disk of a thickness predetermined with reference to certain of the marginal elevations on the platen, and a platen engaging clamp provided with clamping 150

members adapted to simultaneously engage the platen-supported fuel and the elevations on the platen in correspondence with which the thickness of the fuel is predetermined, said clamp 5 having other fuel clamping members adapted for engagement with said fuel at points intermediate of its margins. 7. A vulcanizer of the class described having in combination, a fuel containing platen having therein a consolidated fuel unit of predetermined heating capacity, a clamping spider having platen engaging arms and intermediate depending fuel engaging projections distant from the platen engaging portions of said arms and adapted to engage portions of the fuel unit at points spaced inwardly at a substantial distance from its margins, said projections being of a length predetermined with reference to a prepared fuel of predetermined thickness, and adapted to apply clamping pressure to such fuel simultaneously with the engagement of the clamping spider with the platen, whereby the central portions of the fuel may be held to the platen during combustion notwithstanding the development of gases and warping tendencies. 80 85
